SELECTIVE SWITCH

Earle G. Henry, Chicago, Ill., assignor to Buckley
Music System, Inc., a corporation of Illinois

Application August 26, 1939, Serial No. 292,098

5 Claims. (Cl. 200—11)

It is common practice to provide selective control for musical instruments as, for example, a phonograph apparatus adapted to contain a considerable number of records. Where remote control is employed, the master controller is usually in the form of a selective switch, having as many positions as there are records to be played and each position corresponding to a given record. When payment must be made for the playing of a record, it is customary to associate with the selective controller a suitable-coin-controlled switch or the like in the circuit containing the selective switch. Thus, whenever the selective switch is in any one of its working positions and the coin-controlled switch is closed, the mechanism of the playing machine or apparatus is set to play the record corresponding to that position of the selective switch, either immediately or in its proper order. Usually, the solenoids or the like that are controlled by the selective switch need to be energized for only an instant in order to accomplish their purpose. Therefore, if the movable member of the selective switch be operated very rapidly after a coin has been deposited, it may pass into and through more than one position before the coin-controlled switch opens; thereby setting the playing machine or apparatus so that it will play more than one record instead of a single record for which payment has been made, and thereby defrauding the owner of the playing machine or apparatus.

The object of the present invention is to produce a simple and novel selective switch which will make it impossible to cause the playing of more records than the number for which the proper number of coins have been deposited. Or, viewed in another of its aspects, the present invention may be said to have for its object to insure that when a coin is deposited in a coin-controlled selective switch apparatus, only one new circuit can be closed by the switch during any movement thereof following the depositing of a coin.

In the usual coin-controlled device, wherein the coin momentarily closes a circuit, there is practically no variation in the time during which the circuit remains closed during any one of an indefinite number of closures. Therefore, if a selective switch, associated with the coin-controlled switch, is so constructed that when it is shifted from any given position, it cannot close a circuit in any other position until a lapse of time almost as great as that during which the coin-controlled switch remains closed, it will not

enable a person depositing a coin to move the selective switch arm rapidly and thus produce a wiping action over two or more stationary contacts while the coin-controlled switch remains closed; for, the selective switch will close only in that position reached by the moving arm just before the coin-controlled switch opens. Thus, any positions passed through, during the movement of the switch arm, might as well not have been there, so far as any playing of records corresponding to those positions is concerned.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a central vertical section through a selective switch embodying the present invention, the switch being shown in the actual position which it occupies in an actual wall box; Fig. 2 is a rear view of the switch, namely a view of that side which is at the right in Fig. 1; and Fig. 3 is a view similar to Fig. 1, showing the switch open, or it may be said to be a section on line 3—3 of Fig. 2 while the swinging switch arm is in the position shown in dotted lines in Fig. 2.

Referring to the drawing, 1 is a disk of insulating material provided with a series of contact pieces 2 arranged in spaced relation in a circle having its center coinciding with the center of the disk. The contact pieces may conveniently be in the form of rivets whose rounded heads serve as the actual contacts and to the ends of whose stems wires, not shown, may be soldered. The disk is fixed on a central hub 3 carried by a metal sleeve 4. The sleeve is shown as passing through a supporting bar 5 adapted to be fixed within the coin box. A nut 6 screwed upon the sleeve outwardly from the bar 5, serves to clamp the latter against the hub 3 and thus hold the disk stationary. Extending through the sleeve is a short shaft 7, shown as being provided at its forward end with a finger 8 by means of which it may be operated. On the inner end of the shaft behind the disk is a thick collar 9 fixed to and projecting from one side of a thin slab 10 of insulating material, near one end of the latter, which serves as the movable arm for the switch. The member 10 is held in place and also reenforced by a metal plate 11 lying flat against the rear side thereof and fixed

to the part 9, conveniently by having the rear end of the part 9 extend through the plate and being riveted over.

The movable contact element is in the form of a pin or plunger 12 extending through the free end of the arm 10 at right angles to the latter and to the disk; the distance of the element 12 from the axis of the switch corresponding to the radius of the circle in which the stationary 10 contact pieces are arranged. The contact element 12 is slideable lengthwise in its support, but is normally held in its forward or working position by a coil spring 14 surrounding the same and bearing at one end against the rear face of a 15 head 15 on the front end of the element; the rear end of the spring bearing against a bushing or sleeve 16 fixed in the switch arm and constituting the actual bearing for the contact element.

On the rear side of the disk 1 is a metal disk 20 17, smaller in diameter than the disk 1, so as to lie wholly within the circle of contact pieces 2. This metal disk contains a series of frusto-conical holes 18 corresponding in number and in angular distribution to the contact pieces 2. On the 25 switch arm is a suitable dog device adapted to engage in the frusto-conical seats or depressions 18, one after another, as the switch arm is turned; this device yieldingly locking the switch is in any working position into which it may be 30 brought. In the arrangement shown, the dog comprises a metal cup-shaped member 19 lying on the front side of the switch arm with its open end directed forwardly and having at its rear end a neck or stem portion extending through 35 36 and riveted to the switch arm; a ball 20 arranged in and projecting from the open end of the member 19; and a compression spring 21 within the cup-shaped member and behind the ball.

Having only the parts heretofore specifically 40 described, a turning of the switch arm, no matter how rapid, would permit the head 15 on the movable contact element to engage any desired number of the stationary contact pieces in succession. In order to prevent this when the movement is so rapid that the movable contact element 45 can pass two or more stationary contact pieces during the amount of time that usually elapses between the closing and the opening of a circuit by a coin deposited in a coin slot, I have provided the means which I shall now describe. Lying 50 behind and approximately parallel to the switch arm is a long lever 23 which is approximately as long as the diameter of the disk, so as to project far beyond the inner end of the switch 55 arm. The lever has a hole therethrough at one end, and the contact pin 12 extends loosely through this hole; the pin having thereon a washer 24 bearing against the rear side of the lever and held in place by a cotter pin 25. The 60 lever is provided with a second hole 26 on the same side of the axis of the switch as contact element 12. A pin or projection 27, fixed to the switch arm, extends loosely through this hole 26 and has thereon, behind the lever, a washer 65 28 held in place by a cotter pin 29. On the free end of the lever is a comparatively heavy weight 30.

The yieldable dog device for holding the switch arm in its various positions lies between the pin 70 27 and the contact element 12. In addition to the parts heretofore described, the locking dog is provided with a loose pin 31 arranged axially thereof behind and in contact with the ball 20 and extending through the rear end of the cup-shaped part 19 into engagement with the lever 23. 75

Normally the parts of the device are as shown in Fig. 1 and in full lines in Fig. 2, the ball 20 resting in one of the seats or depressions 18, and the contact element 12 resting on one of the stationary contact pieces 2. Upon turning the shaft 5 1, the ball 20 is forced upwardly out of the seat or depression which it previously occupied, and is compelled to ride upon the flat surface of the metal disk 17. As the ball is lifted out of its seat in the disk 17, it forces the pin 31 rearwardly 10 against the lever 23. The washer 28 on the pin 27 prevents the lever from moving bodily in the rearward direction, and therefore the lever must rock about the cotter pin 29 as a fulcrum, the end to which the contact pin 12 is connected being forced away from the switch arm and drawing the head 15 of the contact element away from the plane of the stationary contact pieces, as shown in Fig. 3. When the movable contact element comes into registration with the next stationary 20 contact piece, the ball again drops into a seat or depression and the spring 14 can then exert a pressure on the end 15 of the movable contact element, tending to force that element into engagement with the stationary contact piece with 25 which it registers.

During ordinary operation of the switch, the spring 14 is able to close the switch before the operator or customer is likely to shift the switch arm past any working position into which it has 30 just been brought. However, if it is attempted to turn the switch arm so rapidly that it will move through at least one working position and into the next working position before the switch actuated by a coin can open after having been closed 35 by the insertion of a coin, the inertia of the weight or mass 30 serves to oppose the spring 14, and the action of the latter is slowed down to such an extent that no contact will be made as the switch arm is travelling past the first working 40 position. In other words, if the operator or customer tries to turn the switch arm at an excessively high speed, in the hope of getting the benefit of more than one selection upon depositing a single coin, he will not succeed in his 45 purpose.

No wiring has been shown, although the metal disk 17 may serve as a common terminal adapted to be connected to all of the stationary contact pieces. In order to provide a good conductive 50 path for the current from the contact element 12 to the disk 17, I connect the bushing 16 and the cup-shaped member 19 of the locking dog together by means of a jumper 32. Current may thus flow from a contact-piece 2 through the element 12, the jumper 32, member 19, spring 21 and ball 20 to the disk 17, whenever the selective switch is closed, as in Fig. 1.

While I have illustrated and described with particularity only a single preferred form of my 60 invention, I do not desire to be limited to the exact structural details thus illustrated and described; but intend to cover all forms and arrangements which come within the definitions of my invention constituting the appended claims. 65

I claim:

1. The combination with a series of spaced contact pieces arranged in the arc of a circle, an arm adapted to swing about the center of said circle, and a contact element carried by said arm in position to ride over said contact pieces one at a time upon swinging the arm; of a spring tending to press said contact element against any contact piece underlying the same, means acting in opposition to said spring to raise said element 70 75

and keep it raised while it is moving from one contact piece to the next, said means including a rocking lever mounted on the arm and connected at one end with said contact element and having a counterweight at the other end.

2. The combination with a series of spaced contact pieces arranged in the arc of a circle, an arm adapted to swing about the center of said circle, and a contact element carried by said arm in position to ride over said contact pieces one at a time upon swinging the arm: of a mounting for said contact element on the arm to permit it to be shifted from and toward the plane of the contact pieces, a spring acting on said element to move it toward the contact pieces, a lever mounted on said arm for rocking movements, one end of the lever being connected to said element, a weight on the other end of the lever, and means to shift said element away from said plane while it is travelling with the arm from one contact piece to the next.

3. The combination with a series of spaced contact pieces arranged in the arc of a circle, an arm adapted to swing about the center of said circle, and a contact element carried by said arm in position to ride over said contact pieces one at a time upon swinging the arm: of a mounting for said contact element on the arm to permit it to be shifted from and toward the plane of the contact pieces, a spring acting on said element to move it toward the contact pieces, a lever mounted on said arm for rocking movements, one end of the lever being connected to said element, a weight on the other end of the lever, a yieldable dog mounted on said arm, an arc-shaped track over which said dog rides during swinging movements of the arm, said track being shaped to interlock with the dog whenever said contact element registers with a contact piece and yieldingly hold the arm against swinging movements and to raise the catch and hold it raised while the contact element is travelling from one contact piece to the next, and a part on said dog to actuate the lever and shift said contact element away from the said plane whenever the dog is raised.

4. The combination with a series of spaced contact pieces arranged in the arc of a circle, an arm adapted to swing about the center of said

circle, and a contact element carried by said arm in position to ride over said contact pieces one at a time upon swinging the arm: of a mounting for said contact element on the arm to permit it to move lengthwise from and toward the plane of the contact pieces, a spring acting on said element to move it toward the contact pieces, a lever mounted on and approximately parallel to said arm for rocking movements, one end of the lever being connected to said element, a weight on the other end of the lever, a dog including a member slidably mounted in said arm parallel to said contact element and engaged with the under side of said lever, an arc-shaped track over which said dog rides during swinging movements of said arm, said track having depressions corresponding in angular positions to said contact pieces and into one of which said dog drops whenever said contact element rests on one of said contact pieces.

5. The combination with a series of spaced contact pieces arranged in the arc of a circle, an arm extending radially of and adapted to swing about the center of said circle, and a contact element carried by the free end of said arm in position to ride over said contact pieces one at a time upon swinging the arm: of a mounting for said contact element on the arm to permit it to move lengthwise from and toward the plane of the contact pieces, a spring acting on said element to move it toward the contact pieces, a lever about twice as long as the arm mounted on and approximately parallel to the latter for rocking movements, one end of the lever being connected to said element about an axis between the ends of and transverse to the axis of rotation of the arm, a weight on the other end of the lever, a dog including a member slidably mounted in said arm parallel to said contact element and engaged with the under side of said lever, an arc-shaped track over which said dog rides during swinging movements of said arm, said track having depressions corresponding in angular positions to said contact pieces and into one of which said dog drops whenever said contact element rests on one of said contact pieces.

EARLE G. HENRY.
